(57) **CLAIM**

We claim the ornamental design for a portable power manager enclosure, as shown and described.

DESCRIPTION

FIG. 1 is a perspective view of the top, front, and left side of a portable power manager enclosure showing an embodiment of the new design;

FIG. 2 is a top view thereof;

FIG. 3 is a left side view thereof;

FIG. 4 is a front view thereof;

FIG. 5 is a right side view thereof; and,

FIG. 6 is a bottom view thereof.

The broken line showing of the portable power manager enclosure is for the purpose of illustrating environmental structure and forms no part of the claimed design.
